CLAIM

What is claimed is the ornamental design for the “abrasive resistant pad,” as shown and described.

DESCRIPTION

FIG. 1 is a perspective view of the “abrasive resistant pad”; FIG. 2 is a top view of the “abrasive resistant pad”; FIG. 3 is a bottom view of the “abrasive resistant pad”; FIG. 4 is a side view of the “abrasive resistant pad”, all sides of the pad being identical; and, FIG. 5 is a perspective view of the “abrasive resistant pad” shown in use with an open-cell concrete block.

The broken line showing of open cell concrete block is for illustrative purposes only and forms no part of the claimed design.
